LIFTING DEVICE FOR SUBSTRUCTURE
COVERS

Gilhome W. J. McMillan, Montebello, Calif.

Application November 26, 1948, Serial No. 62,028

1 Claim. (Cl. 294—17)

1

This invention relates generally to lifting devices and particularly to a tool designed especially for facilitating lifting and removal of vault covers and like relatively heavy objects.

It is customary when removing manhole covers and similar heavy vault covers from their supporting frames to employ various types of lifting tools or apparatus to facilitate such removal. One such tool consists merely of a lifting iron, an end of which is inserted between the cover and its frame, the tool being pivoted downwardly to pry a side of the cover upwardly. When extremely large heavy covers are to be removed, it has heretofore been necessary to utilize a block and tackle apparatus which functions to lift the cover vertically from its supporting frame. While such prior lifting means are capable of lifting the covers, providing the latter are free in their supporting frames, it is well known that the covers frequently become locked in their frames, due to rusting, the accumulation of foreign matter, or the presence of ice and snow, and when such a condition exists, it is difficult to loosen and remove the covers. Moreover, when covers of the large, heavy types are to be removed, the large, cumbersome hoisting apparatus must be transported to the site and set up for operation above the cover, and such equipment utilizes space in the work truck which might otherwise be used to greater advantage.

It is an object of this invention to obviate the disadvantages of prior lifting devices by providing a single device which is capable of lifting both relatively light weight and relatively large, heavy manhole covers and similar covers of vaults and the like. A related object is to provide a lifting device which is operative to raise one side of a vault cover, with the cover pivoting at its opposite side, the device being so constructed that it is detachably connected to the cover so that, subsequent to the tilting of the cover, the latter can be readily slid laterally from its supporting frame by exerting a pull on the device.

Another object is to provide a lifting device or implement which, due to its length, is capable of exerting an upward force sufficient to not only raise a relatively free cover but also to loosen covers which are locked in their supporting frames due to rust, ice, etc. By this provision, a workman can readily apply a lifting force against the cover while assuming a natural and comfortable stance so that injury to the workman, due to excessive strain, is effectively avoided.

Another object is to provide a lifting device of the character referred to, which is adapted to be

2

operated manually when covers of the smaller types are to be lifted, or capable of being actuated by a conventional jack so as to produce the upward force necessary to free and raise relatively large, heavy covers.

Another object is to provide a device of the type indicated which is relatively simple in construction, economical to manufacture and adapted to be stored or transported in a small space.

A further object is to provide a device of the type specified which is self-adjusting so that it can be used in connection with vault covers of various forms without requiring manual adjustment of its parts.

Further objects of the invention will be apparent from the following specification, and from the drawing, which is intended for the purpose of illustration only, and in which:

20 Fig. 1 is a perspective view of the present lifting device showing it applied to use for lifting a vault cover;

Fig. 2 is an enlarged side view of the same;

Fig. 3 is a bottom view of the lifting device;

25 Fig. 4 is a cross-sectional view, taken on line 4—4 of Fig. 2;

Fig. 5 is a cross-sectional view, taken on line 5—5 of Fig. 2; and

30 Fig. 6 is a fragmentary side view of the device, illustrating the manner in which a jack is employed therewith for obtaining the upward force necessary to lift a large, heavy cover.

Referring to the drawing in detail, my lifting device 9 or implement comprises a relatively long bar 10 which, as shown in Figs. 3 and 4, is constructed from sheet metal bent into channel-shaped cross section, the bar having a top wall 11 and depending side walls 12 and 13. At one end, the top wall 11 of the bar 10 is extended to provide a strip 14 which is bent around a tube 15 extending transversely across this end of the bar, the strip being welded or otherwise secured to the tube and to the lower edges of the side walls 12 and 13. The tube 15 provides a handle by which the implement or tool can be manually operated.

35 45 The end of the bar 10, opposite to the handle end, is curved as indicated at 17 and welded to this curved end is an arcuate shoe 18 which is adapted to rest upon the upper surface of a cover 20 to be lifted, the shoe also serving as a pivot about which the tool can tilt within limits when connecting the tool to the cover.

Spaced inwardly from the shoe 18 and extending transversely through apertures in the side walls 12 and 13 is a bolt 22 which has a head 23

at one end abutting the wall 12 and a nut 24 screwed onto its other end to retain the bolt in place. Surrounding the bolt 22 within the bar 10 is the bearing sleeve 25 of a U-shaped element 26 which is thus pivoted on the bolt. The pivoted element 26 carries a hook member 27. The hook member 27 is thus pivotally mounted on the bar 10 and adapted to move freely in either direction. Pivotal movement of the hook member 27 is limited in one direction by its engagement with the curved shoe 18 and in the opposite direction by a stop plate 28 disposed between the side walls of the bar.

Secured to the top wall 11 of the bar 10 adjacent the shoe 18 is a hook-shaped lifter element 30. Welded to the bottom of the bar 10 at a point substantially midway of the length thereof is an angular rest 31 which is used for the purpose to be later explained.

Assuming that it is desirable to remove the manhole cover 20 from its supporting ring or frame 36 and that the cover is one of a smaller type capable of being lifted manually, the present lifting device is applied to use in the following manner to facilitate removing the cover. Manhole and similar covers are usually provided with either cross-pins 34 disposed in small wells 35 (Figs. 1 and 2) or with apertures 35' as illustrated in Fig. 6, the pins 34 or the lower edges of the sides of the apertures 35' providing means which can be engaged by a lifting tool or lifting apparatus. To apply the present tool to use in lifting the cover 20, the tool is placed in inclined position with its curved shoe 18 resting upon the top of the cover as shown in Figs. 1 and 2. The hook member 27 pivots downwardly under the influence of gravity and by guiding the member into the well 35 the member is caused to engage the pin 34. To remove the cover 20, a manual upward force is applied against the handle 15 of the lifter bar 10 and, due to the fact that the tool cannot pivot upwardly relative to the cover, pivotal movement of the tool effects simultaneous pivotal movement of the cover, the latter pivoting at the side opposite to that to which the tool is connected. After the edge of the cover 20 clears the corresponding edge of the supporting frame or ring 36, a lateral pull exerted on the tool causes the cover to be slid out of the frame onto the surface of the roadway 37 or other surrounding area.

The length of the tool, which may be, for example, 3 feet, when added to the diameter of a common type cover 20 provides a second-class lever, the effective length of which might be approximately 5 to 7 feet. It is thus apparent that the mechanical advantage derived through the use of the instant lifting device is considerable and consequently the applied force required to pivot the vault cover is much less than that necessary when tools of previous types are employed. Through the increased leverage, sufficient force can be applied to dislodge or free a cover from its supporting frame even when the cover is wedged therein due to the accumulation of rust, ice, etc.

If it is desired to lift the entire cover 20 vertically and move the same onto the surface 37, a pair of the lifting devices 9 is employed. In this case, the hook members 27 of the two devices 9 are engaged with the pins 34, or the edges of the apertures 35', which are disposed at diametrically opposite points on the cover, and the two lifting devices are simultaneously raised so

as to cause straight upward movement of the cover 20, it being noted that when two of the devices are employed the cover will not pivot. After the cover 20 has been lifted from its supporting frame 36 by two workmen in the manner last explained, the cover is moved laterally, with the devices 9 serving as handles, and lowered onto the surface 37.

In some vaults, a sub-cover or auxiliary cover 38 (Fig. 2) is employed for preventing foreign matter from dropping through the openings of the main cover into the vault. Such an auxiliary cover is usually light in weight and can be readily removed from the ring 36 which supports it by inserting a suitable hook through a loop 39 of the cover and lifting the latter. The present lifting device 9 is provided with means for facilitating the removal of such an auxiliary cover. This means consists of the lifter hook element 30 which is adapted to be hooked through the loop 39 of the auxiliary cover 38, the device 9 then serving as a long handle by which the cover 38 can be lifted from the vault opening.

As previously pointed out, when large, extremely heavy manhole covers are to be removed so as to gain access to the manhole, considerable difficulty is experienced because of the strain imposed on workmen attempting to pry the cover from its supporting frame. To alleviate this condition, lifting apparatus employing block and tackle means have been employed for lifting the covers and subsequently lowering the same onto suitable rollers by means of which the removed covers can be moved away from the manholes. While such hoisting apparatus is commonly employed and is quite efficient in use, it is relatively large and bulky and requires considerable space in the repair truck which transports it to the site and, moreover, it must be set up and adjusted above the manhole. The present lifting means is capable of lifting such relatively large, heavy vault covers, such a cover 40 being shown in Fig. 6 as supported by a ring or frame 41.

To lift the heavy cover 40, the lifting device 9 is connected to the cover in the manner illustrated in Fig. 6, that is, with its curved shoe 18 resting upon the top of the cover and its hook member 27 engaged with the edge of the aperture 35'. In order to augment the applied upward force and thus relieve the strain which might otherwise be imposed on the workman performing the lifting operation, the present invention contemplates the provision of means for mechanically applying the necessary force. In Fig. 6 the force applying means consists of a conventional vehicle jack 42 which may be either of the mechanically or hydraulically actuated types. After the lifting device 9 has been positioned as shown in Fig. 6, the jack 42 is moved to a position 50 wherein its force applying element 43 is disposed beneath the angular rest or abutment 31. By operating the handle 44 of the jack 42, the jack element 43 is moved upwardly with sufficient force to effect pivotal movement of the lifting device 9 and the vault cover 40 connected thereto. When that portion of the cover 40 to which the device 9 is connected clears the top of the supporting ring 41, a suitable roller, such as a length of circular rod or pipe, is slid under this portion and the device 9 disconnected from the cover. The lifting operation explained above is then repeated at the opposite side of the cover 40 to elevate the latter above the ring 41 and to permit the placing of a second roller under the 55 cover. With the cover 40 thus completely re-

moved from the ring 41, it can be readily moved on the rollers (not shown) along the surface 45 to uncover the vault opening. As will be apparent, the magnitude of the upward force obtainable through the use of the jack 42 is such that the large, heavy cover 40 can be readily freed from the supporting ring 41 even when these parts are wedged or adherently joined by rust, dirt or ice.

It will be observed from the foregoing that my invention provides a simple, yet highly efficient means for removing covers from the openings of manholes, vaults and other subterranean chambers. The improved lifting device can be readily transported and conveniently connected to a cover to be lifted and quickly disconnected therefrom following the lifting operation. By means of the present device the force applied by the workman is multiplied so that large, heavy covers can be readily removed when the covers have the tendency to resist removal due to the accumulation of dirt, rust, ice or other foreign matter between the cover and its supporting frame. Since the lifting force is applied while the workman assumes a natural and comfortable stance, injury to the workman, due to excessive strain is avoided. As another feature of the present invention, the improved lifting tool is adapted to be used in conjunction with a jack which is capable of exerting an upward force against the tool necessary to dislodge and elevate the vault cover. Moreover, the present lifting tool is economical to manufacture, is strong and durable, and is adapted for use in removing all of the various types of vault covers now in common use.

While the vault cover removing tool or implement has been herein described as embodied in a preferred form of construction, by way of example, it will be apparent that it is susceptible of various modifications which fall within the scope of the appended claim.

I claim as my invention:

A lifting device adapted for lifting a vault

cover, said cover having an internal abutment by which it can be lifted from a supporting frame, comprising: a lifter bar of channel shape cross section having a top wall and depending side walls, the bottom edges of said side walls at one end of said bar terminating in curved surfaces; a curved elongate shoe secured to and extending between said curved surfaces, said shoe being restable against the exposed surface of the cover; a transverse handle secured to the other end of said bar; and a hook member pivoted between said side walls adjacent said shoe and having a curved hook portion engageable beneath said abutment of the cover, said shoe and said hook member together rigidly connecting said lifter bar to the cover, when an upward force is applied to said bar through said handle, so as to effect unitary pivotal movement of said bar and the cover with respect to the supporting frame, said curved shoe being wider than said bar so as to provide a bearing surface of sufficient width to avoid excessive longitudinal axial rotation of said bar with respect to the cover upon which said shoe rests.
